CLAIM

The ornamental design for an insole, as shown and described.

DESCRIPTION

FIG. 1 is a perspective view of an insole in accordance with an embodiment of our new design;
FIG. 2 is another perspective view thereof;
FIG. 3 is a top plan view thereof;
FIG. 4 is a bottom plan view thereof;
FIG. 5 is a right side elevation view thereof;
FIG. 6 is a left side elevation view thereof;
FIG. 7 is a front elevation view thereof;
FIG. 8 is a rear elevation view thereof;
FIG. 9 is a perspective view of an insole in accordance with another embodiment of our new design;
FIG. 10 is another perspective view thereof;
FIG. 11 is a top plan view thereof;
FIG. 12 is a bottom plan view thereof;
FIG. 13 is a right side elevation view thereof;
FIG. 14 is a left side elevation view thereof;
FIG. 15 is a front elevation view thereof; and,
FIG. 16 is a rear elevation view thereof.

The broken lines in the figures illustrate portions of the insole that form no part of the claimed design.

1 Claim, 8 Drawing Sheets
